UNITED STATES PATENT OFFICE.

OTHO C. DURYEA, OF KNOXVILLE, TENNESSEE.

DISPLAY SIGN.

Application filed July 1, 1924. Serial No. 723,591.

This invention relates to display signs, and more particularly to a device of this character which is designed to be illuminated intermittently by the movement of a door or other closure. The construction of devices of this character as heretofore employed has involved cutting the door or the door-case to apply the sign thereto, and as these signs are usually applied to the entrance doors of business places, the cutting of the door or door-case in installing the signs renders a new door or door-case necessary if the sign is removed. Moreover, would-be users are hesitant about applying the sign to a door or door-case when such cutting of the door or case is involved. Furthermore, where such cutting or material defacing of the door or door-case is involved, the cost of installation is much increased and requires mechanics of a high grade to install the sign.

The object of the present invention is to provide a sign of the general character indicated which may be applied to the door or door-case without cutting or removing any part of the door or case and without defacing the same, and furthermore, to provide a sign which may be easily and quickly installed by an ordinary mechanic, to the end that the expense of the installation shall be reduced to a minimum.

With these objects in view, the invention, generally stated, consists of a sign carried by a suitable sign-casing, which casing is attached directly to the face of the door or door-case, an electric lamp or lamps in said sign-casing, together with electric circuits leading to an outside source of electrical energy under the control of the swinging movements of the door or door closure, to the end that the electrical current may be switched on and off by the opening and closing movements of the door, all without cutting into or defacing the door so that, if said sign is removed therefrom, the door remains practically uninjured. By thus mounting the sign and the illuminating lamp therefor in a sign-casing, all that is required for the same to be installed is to attach the sign-casing and the switch for controlling the circuit to the face of the door or the door-case, and install the necessary electric circuit.

The sign may be of any desired or suitable form, such for example as a simple sign or a series of signs arranged to be brought into

use step-by-step at each swinging movement of the door, or otherwise.

For the purpose of illustrating the invention, there is herein shown a rotatable element which presents step-by-step a series of signs at each swinging movement of the door, the rotation of the said element being preferably controlled by electrical means likewise under the swinging movement of the door. By the use of such rotatable sign, a different advertisement may, if desired, be shown and illuminated each time the door is opened, but as hereinbefore indicated the sign may, if desired, be a single sign which is shown and illuminated at each closing movement of the door, without departing from the broad spirit of the invention.

The inventive idea involved is capable of receiving a variety of mechanical expressions, some of which, for the purpose of illustration, are shown in the accompanying drawings, but it is to be expressly understood that the drawings are for purposes of illustration only and are not to be construed as defining the limits of the invention, reference being had to the appended claims for this purpose.

In said drawings:—

Fig. 1 is a fragmentary elevation of a door-frame and door viewed from the inside, showing my invention installed thereon;

Fig. 2 is an edge view of the door, looking from the right of Fig. 1;

Fig. 3 is a fragmentary elevation of the door viewed from the outside, showing an illuminated sign or advertisement;

Fig. 4 is a view similar to Fig. 3, the sign or advertisement not being illuminated;

Fig. 5 is a front elevation on an enlarged scale, showing a door-operated switch;

Fig. 6 is a side elevation of the switch shown in Fig. 5;

Fig. 7 is a front elevation of the sign box on an enlarged scale;

Fig. 8 is a vertical sectional view through the sign box of Fig. 7;

Figs. 9, 10 and 11 are sectional views on the respective lines 9—9, 10—10 and 11—11 of Fig. 8;

Fig. 12 is an enlarged sectional detail showing operative connections between the armature of an electromagnet and the sign drum;

Figs. 13, 14 and 15 are elevations of another form of door showing a sign box

installed thereon and a modified form of switch.

Referring to the drawings, 5 indicates a door of any suitable form, here shown as mounted by means of hinges 6 and 7 on a door-frame 8 above which is disposed a transom 9. A sign-box, constituting the sign-casing and designated broadly at 10, is supported on the outer side of the door, preferably at a height in the line of vision of persons entering the store or establishment where the device is installed. The sign-box may, however, be mounted on the door-case or upon an independent support, 15 or otherwise positioned within view of persons passing in and out of the building. Said box comprises a base 11 to which is secured a cover 12 provided in its front face with an opening 13 in which is disposed a 20 plate 14 of glass or other transparent material.

Referring more particularly to Figs. 8-11, inclusive, 15 designates a carrier in the form of a reel or drum, here shown as 25 hexagonal in cross-section, the sides of said drum being perforated to provide stencilled advertising legends visible on plate 14 when the device is illuminated in a manner hereinafter described. The drum is telescoped 30 over a fixed reflector casing 16 secured at its lower end, as by solder or other suitable means, to a bracket 17 extending from base 11 of the box. The upper end of drum 15 projects through an annular opening in 35 a bracket 18 extending from base 11. Rollers 19 and 20 mounted in annular grooves at the end of the drum bear upon annular portions of the reflector casing whereby the drum may rotate about the 40 casing and present stencilled signs or legends successively at opening 13 of box 10.

Electric lamps 21 and 22 are mounted in suitable sockets 23 and 24 secured on the ends of reflector casing 16, and as here 45 shown are concealed from view through opening 13. The casing is provided with an opening 25, registering with opening 13, and with curved reflecting surfaces 26 and 27, whereby when the lamps are lighted the 50 rays are directed through the perforations of the drum causing the advertisements or legends to appear on plate 14. Drum 15 has fixed on its upper end a ratchet wheel 28 and said wheel and drum are adapted to 55 be rotated by a pawl 29 mounted on an arm 30 fixed on a rotatable sleeve 31. Sleeve 31 is loosely mounted on a stub shaft 32 of ratchet wheel 28 and said shaft and sleeve telescope within the hollow tubular armature 60 33 of an electromagnet 34. Armature 33 is provided with a key 35 engaging in a groove 36 of the magnet spool, so that while the armature may move in a longitudinal direction it is prevented from rotating by the 65 key and groove above described. A spring 37

surrounds the armature, one end of said spring bearing against the magnet spool and its opposite end bearing against an annular flange on the armature. Longitudinal movement of the armature is converted into 70 rotary movement of the ratchet mechanism by a pin 38 on the armature which engages in a spiral groove 39 of sleeve 31.

Electrical current is supplied to lamps 21, 22, and magnet 34 by line wires 40 and 41, 75 illumination of the lamps and operation of the magnet being controlled by a switch 42 preferably secured on door-case 8 and interposed in the line provided by said wires. The switch is provided with any suitable 80 means for throwing the same, here shown as a forked operating lever 43, pivoted on the switch casing by means of a bolt or pin 44. The forked end of lever 43 is adapted to engage a detent 45 secured on the door; this engagement being effected on initial movement of the door to open the same and upon final closing movement of the door. The switch, magnet and lamps are connected in parallel with the source of electrical current by means of leads 46, 47, 48, 49 and 50, 51, the circuit and connections being shown diagrammatically in Figs. 1 and 8.

On initial movement of door 5 to open the same, detent 45 will swing switch lever 43 to the dotted line position shown in Fig. 6, thereby closing the circuit to the lamps and magnet, causing the lamp to light and energizing the magnet. Current flowing through the magnet windings causes 100 armature 33 to be drawn within the magnet spool, thus compressing spring 37. Inward movement of the armature causes pin 38 to travel in spiral groove 39 of sleeve 31, thereby imparting rotary movement to the latter 105 and causing arm 30 to move in a clockwise direction to the dotted line position shown in Fig. 10. A pawl 29' engaging the ratchet wheel prevents movement of drum 15 when arm 30 is rotated in the clockwise 110 direction. In the final closing movement of door 5, detent 45 again engages switch lever 43, swinging the same to the full line position shown in Fig. 6, thereby breaking the circuit to the lamps and magnet. 115 Spring 37 then withdraws the armature from the magnet spool, causing the pawl and ratchet mechanism to move in a counter-clockwise direction until the pawl contacts with a stop 30'. This counter-clockwise movement of the pawl and ratchet mechanism causes partial rotation of drum 15 in the same direction so that the next time the door is opened and the lamps lighted, a different sign or advertisement 120 will be displayed on plate 14. The arrangement and operation of the parts is such that each time the door is opened and closed, drum 15 will be moved one step, whereby 125 the signs are successively displayed by suc- 130

cessive opening and closing movements of the door.

Figs. 13 to 15 inclusive show a sign-box 52 mounted on a screen door 53. The switch 54 may be of any well known type having a spring normally holding the contacts apart. Said switch is housed in a suitable recess in one side of the door, and is provided with a push plate 55 secured on 10 a movable part 56 of the switch. Plate 55 is attached to the free ends of guard bars 57, 57 which extend across the screen panel, said bars being pivotally mounted at their opposite ends on pivots 58, 58 of a bracket 15 59 secured on the door. Line wires 60, 60, in which switch 54 is interposed, supply electrical current to the lamps and magnet (not shown). Pressure against the push plate or guard bars to open the door will 20 close the switch, whereupon the sign will be illuminated and displayed as above described. When the push plate and guard bars are released to let the door swing closed, the switch spring acts to restore the 25 parts to their normally inoperative position, the circuit to the lamps and magnet thus being broken as the door is closing.

It will be observed that by mounting the sign, the lamp and the reflector for illuminating the same and other incidental parts all in a single box or casing, which box or casing may be attached to the face of the door or door-case, all necessity for cutting away any part of the door or otherwise defacing it is obviated. Moreover, the switch mechanism for controlling the flow of current to the lamp is so mounted that no defacement or cutting of the door or door-case is required. Both these parts, to wit, the box or sign-casing and the switch mechanism, can be quickly and readily installed by an unskilled mechanic. These features enable the sign to be constructed and installed at a minimum price and therefore places such signs within the means of a large number of dealers to whom the more expensive and more complicated signs would be prohibitive.

What is claimed is:—

- 50 1. In combination, a door, a sign casing removably mounted on the face of the door, a movable sign within the casing, a lamp within the casing for illuminating the sign, electrically actuated means for moving the sign, a door frame, a switch removably mounted on the door frame, an electric circuit including the electrically actuated sign moving means, the lamp, the switch and a source of electrical energy, and a detent on 55 the door for operating the switch.
- 60 2. In combination, a door, a rotatable sign, means for illuminating the sign, means for moving the sign, and means controlled by movement of the door for actuating said 65 illuminating means when the door is opened

and said sign moving means when the door is closed.

3. In a device of the character described, a door, a sign casing mounted on the face of the door, a rotatable sign within the casing, an expansible spring for rotating the sign, and electrical means controlled by movement of the door for contracting the spring.

4. In combination, a door, a sign casing, a rotatable sign within the casing, a pawl and 75 ratchet mechanism for rotating said sign, an expansible spring for actuating said pawl and ratchet mechanism, a reciprocable armature for contracting said spring, and electrical means controlled by the movement of the 80 door for reciprocating the armature.

5. In combination, a door, a sign casing mounted on the face of the door, a rotatable sign within the casing, a ratchet wheel secured to one end of the sign and provided with a stub shaft, a sleeve loosely mounted on the stub shaft and provided with a spiral groove, a pawl carried by the sleeve and adapted to engage teeth on the ratchet wheel, an electromagnet, a hollow armature 90 reciprocally mounted within the electromagnet and adapted to be retracted when the electromagnet is energized, a spring for normally holding the armature in extended position, a pin carried by the armature and 95 adapted to engage the spiral slot in the sleeve whereby reciprocatory movement of the armature is converted into rotary movement of the sleeve, and an electric circuit controlled by the movements of the door for 100 energizing said electromagnet.

6. In combination, a door, a sign casing mounted on the face of the door, a rotatable sign within the casing, a ratchet wheel secured to one end of the sign and provided with a stub shaft, a sleeve loosely mounted on the stub shaft and provided with a spiral groove, a pawl carried by the sleeve and adapted to engage teeth on the ratchet wheel, an electromagnet, a hollow armature 105 reciprocally mounted within the electromagnet and adapted to be retracted when the electromagnet is energized, a spring for normally holding the armature in extended position, a pin carried by the armature and 110 adapted to engage the spiral slot in the sleeve whereby reciprocatory movement of the armature is converted into rotary movement of the sleeve, a door frame, a switch on the door frame, an electric circuit including the electromagnet, the switch, and a source of electric current, and a detent carried by the door for actuating the switch whereby the electromagnet is energized 115 when the door is opened and deenergized 120 when the door is closed.

In testimony whereof I have signed this specification.

OTHO C. DURYEA.
